UNITED STATES PATENT OFFICE.

WILLIAM H. TUOHY, OF EAGLE, WISCONSIN.

CONCRETE-MOLD.

1,09,803.

Specification of Letters Patent.

Patented Sept. 8, 1914.

Application filed December 27, 1913. Serial No. 808,947.

To all whom it may concern:

Be it known that I, WILLIAM H. TUOHY, a citizen of the United States, and a resident of Eagle, in the county of Waukesha and State of Wisconsin, have invented certain new and useful Improvements in Concrete-Molds; and I do hereby declare that the following is a full, clear, and exact description thereof, reference being had to the accompanying drawings, and to the letters of reference marked thereon, which form a part of this specification.

This invention relates to improvements in concrete molds and more particularly to devices of the character described adapted for use in connection with the construction of retaining walls and foundations of buildings and similar structures involving a sufficient degree of uniformity and regularity in outline as to permit in its construction the repeated use of a manually operable device.

The object of my invention is to provide a concrete mold that is simple in construction and operation and embodying such features as will render it exceedingly flexible and convenient in its application to the art of building in concrete, and thereby decrease the time and cost involved in building operations of that character.

The further advantages and features of my invention will be fully understood from the matters hereinafter described, more particularly set forth in the appended claims and fully illustrated in the accompanying drawings in which—

Figure 1 is a sectional view taken on line 1—1 of Fig. 2, showing one of the frame members of my device in side elevation; Fig. 2 is a view in side elevation, showing the complete device; Fig. 3 is an enlarged detail view of a portion of Fig. 1, showing the arrangement of the operating mechanism of the device; Fig. 3^a is a detail section taken on line 3^a—3^a of Fig. 3; Fig. 4 is a top plan view of a corner portion of a wall in process of construction and an end portion of the mold, showing the manner in which corners are formed; Fig. 5 is a sectional view on line 5—5 of Fig. 4; Fig. 6 is a view similar to Fig. 4, showing the mold shifted to complete the formation of the corner; Fig. 7 is a view in end elevation of a modified form of frame member; Fig. 8 is a perspective view of portions of a mold suitable for the construction of fence posts.

Referring to the accompanying drawings and particularly to Figs. 1 to 7, inclusive, a form of my device is shown as would be used in the construction of a wall of uniform thickness, and herein illustrated as consisting of two sections at right angles to each other, joined at their ends to form a corner. (See Figs. 4, 5 and 6.)

The mold embodying my invention comprises, in general, frame members 11, 11, and mold boards 12 and 13, supported by said frame members. The frame members are spaced a suitable distance apart and arranged in parallel relation to each other and in transverse relation to the said mold boards. The mold boards 12, 13 are secured to the frame members 11, 11 in such a manner that one of said boards, 12, is in fixed relation to the frame members, so as to maintain a vertical position, and the other of said boards, 13, is adjustably or movably attached to the frame members so as to be normally maintained in a position parallel with the board 12, while it is capable of being moved in a direction toward and from said board 12 and out of parallel relation therewith, for the purpose of applying the mold to the wall in position to receive the concrete and to release the mold in the manner hereinafter to be described.

Referring now more in detail to the construction of the frame members, each of the same comprises a rigid frame 14, 14, consisting of two pairs of horizontal bars 15, 16, 90 located one above the other and joined together at their ends by means of connecting members 17, 17, shown as made of curved form. The said pairs of longitudinal bars are also spaced apart laterally, 95 forming a longitudinal space between them, said space being maintained by inserting the ends of the connecting members between the ends of the longitudinal bars, and securing all of the members together 100 by means of rivets 18.

Each of the rigid frames 14, 14 supports two vertical arms 18 and 20, one of the arms, 19, being in rigid connection with the frame, and the other having movable or swinging connection therewith. Said arm 19 is mounted within the space between the horizontal bar members and is secured thereto by means of bolts 21 extending through the upper horizontal bar members 15 and the 110 upper extremity of the vertical arm, and through the lower bar members 16 and the

said vertical arm. The lower portion of said vertical arm 19 projects downwardly below the frame 14 and to the same is fastened the mold board 12. The fastening means shown consists of angle members 22 attached by rivets or otherwise to the outer surface of said board. The other vertical arm 20, which is movable, as stated, is mounted within the space between the longitudinal bar members 15 and 16, at a distance from the arm 19. The arm 20 is pivotally connected to the lower horizontal bar members 16 by means of a pivot bolt 23, the upper extremity of the arm projecting upwardly between the upper bar members 15 and disconnecting therefrom so as to render the arm free to be oscillated about its pivot bolt 23. As in the case of the vertical arm 19, the arm 20 likewise extends downwardly from the frame 14 and is affixed to the mold board 13 by means of similarly arranged angle members 22. Referring now to the mechanism illustrated for operating the said movable arm 20, the same comprises the following elements: A hand lever 24 (Fig. 3) is pivotally mounted between the upper horizontal bars 15, 15, with its pivotal axis immediately adjacent to the path of movement of the upper extremity of the vertical arm 20. Said lever is pivotally supported by means of a pivot bolt 25 extending through the lever a short distance from its lower extremity. The pivot bolt is located on the bars 15, 15 at a short distance horizontally from the arm 20. The lower extremity of the lever is slightly rounded and adapted to have sliding contact with the adjacent edge of the vertical arm 20, when the lever is swung downwardly from its vertical position, as shown in full lines in Fig. 3. The arm 20 is provided with a link member 26 (Figs. 3 and 3a), secured thereto at a point immediately below the horizontal bar members 15, said link extending parallel with said bar members in the direction of the lever 24. The link member is preferably of U-shape, as seen in plan view, and its ends embrace the arm and are secured thereto, by means of a bolt 27. Said link member is adapted to engage, at its outer end, the lower extremity of the lever 24, when the latter is swung or moved toward its vertical position (as shown in dotted lines in Fig. 3), and from its position in contact with the upper extremity of the arm, and by this engagement to transmit a movement to the arm 20 about the pivot bolt 23. The upper end of the lever 20 adjacent to the pivot of the operating lever and the end portion of the link member form bearing surfaces, facing toward each other, on which the lower end portion or arm of the operating lever acts, in one instance to throw the lower end of the arm 20 inwardly and lock the same from movement, and, in the other instance,

to swing the lower end of said arm outwardly. By swinging the lever 24 toward its upright position the upper extremity of the arm 20 is drawn inwardly toward the arm 19 (Fig. 1), and in like manner the lower extremity of the said arm 20 is swung outwardly from the said arm 19, and as a result the space between the mold boards 12, 13 is increased. By swinging the lever 24 downwardly from its vertical position, the lower extremity or arm thereof is disengaged from the link and coacts with the surface of the arm. This engagement between the arm and lever, in the nature of a cam action, effects a movement of the arm 20 in the opposite direction and to a position in which said arm 20 is parallel with the arm 19. The upper extremity of the lever 24 is preferably bent outwardly at right angles to the horizontal bars 15, to form an angular portion 28, the same acting as a stop to limit the downward movement of the lever, as well as a convenient handle for grasping the lever. When said lever is in its maximum downward position with the bent portion in contact with the horizontal bars 15, the lever also acts to lock the movable arm 20 in its vertical position until released by grasping the lever and moving the same upwardly.

Referring more particularly to the construction of the mold boards, the same may be of any desired length and width, depending upon the nature of the work or the size of the mold. The mold boards, as the name suggests, would ordinarily be of wood although other materials such as sheet metal may be employed where the increased weight would not make its use undesirable.

A device embodying the features of construction thus far described, would be limited in its use to the construction of a continuous straight wall of a predetermined thickness having parallel and vertical faces and devoid of angles, corners, openings, or spaces therein. The operation of building such a wall would preferably be accomplished in stages by the repeated use of the mold in the following manner: The first stage is ordinarily constructed by placing the mold upon the surface of the ground or other suitable foundation with the mold boards in parallel position, and filling the space between the mold boards with concrete in plastic condition. After tamping the concrete down, with its top surface even with the upper margins of the boards, the mold is released from the lower part of the wall thereby formed, by actuating the lever 24 in the manner stated. The operation is repeated, by moving the mold endwise to a position in which one extremity of the mold overlaps the end of the wall section just formed, until the first stage is completed. The second stage is similarly formed upon the first stage, the mold in this instance be-

ing supported upon the previously completed part of the wall, by placing the mold, with the movable board in its released position, in such position that the lower margins 5 of the mold boards overlap or embrace the upper portion of the completed portion of the wall, as shown in Figs. 1 and 2, and then swinging the lever 24 to its horizontal position, so that the mold board 20 operated 10 thereby will be drawn inwardly toward the stationary mold board, and a clamping engagement of the mold with the completed part of the wall will be effected. In this manner the several stages are added one 15 upon the other until the entire wall is completed.

To make the device capable of use in the construction of various forms and thicknesses of walls, I have provided certain features in the structure of the mold, which constitute a part of my invention. Referring to these features in detail, I provide, for the purpose of constructing walls of different thicknesses, a plurality of apertures 29 in 20 the upper and lower horizontal bar members 15 and 16 of the frame members 11, (Fig. 1). These apertures are arranged in pairs, each pair being in vertical alignment and adapted to receive the bolts 21, 21, which secure 25 the stationary arm 19 and mold board 12 rigidly to the frame members. By moving the said arms to one or another pair of apertures and securing the same in vertical position by means of the said bolts, the space 30 between the mold boards may thus be varied to permit the construction of walls of different thicknesses.

To render the mold suitable for constructing the corners of buildings or walls meeting 40 at an angle, I provide a construction in the mold boards as follows: At one end of at least one of the mold boards 12 the same is cut away at its lower edge to form a rectangular rabbet 30 (Figs. 1 and 5), such rabbet 45 extending inwardly from the end of the board and upwardly from the lower margin thereof, so as to form an end-portion in the board of reduced width. The length of the rabbet is slightly greater than the thickness 50 of the wall under construction, or the distance between the inner faces of the mold boards, and the vertical width of the rabbet is equal to the width of the lower marginal portion of the mold boards which ordinarily 55 embraces or overlaps the upper portion of the completed wall section, when the mold is clamped in position upon such completed section. In the downwardly facing surface 60 of the mold board, at the rabbeted or cut away portion, I also provide a plurality of notches 31, preferably equidistantly spaced (Fig. 5), the purpose of which is hereinafter described. For use in constructing any one corner, such a rabbet will need to be provided only in the board which is applied to

form the inner surface of the wall, but both boards will commonly be provided with such a rabbet, so that the same mold may be used for forming reversely arranged corners, or those in which the transverse wall, at the 70 corner toward which the mold is moved as the work progresses, extends either to the right or left from the wall section first completed in the formation of the corner.

At the end of the mold boards adjacent to the recess 30, I provide an end board or gate 32, the same comprising a rectangular member, which may be made of wood, provided, upon its outer face and along its side margins, with laterally extending metal flanged members 33, secured thereto. These flanged members overlap the ends of the mold boards and are retained within spaces at the ends of the mold boards, formed by means of angle members 35, 35 secured to the vertical 85 end margins of the outer surface of the mold boards and provided with inwardly extending flanges or parts which are spaced outwardly from the ends of the mold boards. The flanged members 33 are provided at 90 their upper ends with transversely bent portions 34, adapted to project over and engage the upper margins of the mold boards and to thereby afford additional means for retaining the gate securely in place and limiting the downward movement thereof. By 95 this arrangement the gate may be easily removed or applied when desired, and acts to provide an end face for the section of the concrete wall being formed.

The construction of the recess 31 and the gate 32 is particularly useful in the construction of corners, as before stated.

Now, referring to the operation of constructing a corner, Figs. 4 and 5 show the mold in position to construct the first portion of the corner, in which position the mold is clamped or secured to the completed portion 10 of the wall with lower margins slightly overlapping the same, in the manner before indicated. In this position the ends of the mold are extended slightly beyond the end of the completed section 10 and the outer face of the completed section 36, which intersects the section 10 of the wall at right angles thereto. By reason of the fact that the upper surface of the said completed portion 36 of the wall lies in the plane of the upper surface of the completed portion 10, it would obviously be impossible to place the mold in the position suggested, were it not for the presence of the rabbet 30 which permits the end of the innermost board 20 to extend over the wall-section 36, with the upper portion of the said section 36 occupying the said recess. Having clamped the mold to the wall 10 in the position shown in Figs. 4 and 5, the gate is now put in place, the inner surface thereof being in vertical alignment with the end face of the wall section 36.

10. The wall section formed by means of the mold in this position extends to the end of the wall section 10, and is quite independent of the section 36. Having completed this portion, the mold is removed and clamped to the section 36, in a position at right angles to its prior position, as shown in Fig. 6. In this instance, however, the end of the mold not provided with the gate and recess is placed adjacent to the section just completed, in order that the end of the innermost of the two boards 20 may abut against said section, and a smooth joint between the sections forming the corner may be thereby obtained.

15. Furthermore, it is often desirable to insert, between the horizontal sections of the wall, a series of reinforcing wires 37, which are laid upon the surface of the completed portion 10 and bent at the corner to extend along the section 36. The purpose of the notches 32 is, therefore, to permit the said wires to extend at right angles to the mold board 12, without interfering with the proper placement of the mold upon the wall section 10 and the engagement of the section 36 with the recess 30. The use of the recess 31 and the gate 32, in connection with the mold boards made and operating as described, eliminates the necessity of constructing a special corner mold such as is commonly used for forming the intersections of two wall sections meeting at right angles. In addition to its use in connection with the construction of corners, the gate 32 is particularly useful where, in the construction of a wall, a space or open area is desired to be formed, as for instance where windows or doors are to be placed in the walls of a building. In this capacity the gate serves to form the vertical face of the space into which the window or door sash is fitted, in that it provides a vertical end face for each section at either side of the area or opening. It is to be understood in this connection that either or both ends of the mold boards may be arranged to receive a gate 32, and so, also, a rabbet 30 may be formed in any one or all of the ends of mold boards, although for purposes of this invention I have illustrated but a single gate and rabbet. The presence of the additional gate and recess would obviously increase the adaptability and usefulness of the mold to the uses for which it is designed.

20. In Fig. 7 of the drawings is shown a modified construction of a mold more particularly adapted for constructing walls, one face of which is tapered and the other face vertical. Such a construction is often employed in the building of retaining walls, where the resistance of lateral pressure requires a greater thickness of material at the base of the wall than at the top. This form of mold differs from that hereinbefore described only in the arrangement of the frame

members 38 (one of which is shown in Fig. 7.) In this instance, both of the arms 39, 40 are in pivotal engagement with the lower horizontal frame member 41, the arm 40 being mounted and operated in identically the same manner as before described. The upper extremity of the arm 39; however, is not secured to the upper horizontal bar members 42, but is free to oscillate therebetween. Adjacent to the extremity of the arm 39 is attached one end of a turnbuckle 43, the opposite end thereof being secured to the adjacent vertical connecting bar 44. By adjusting the turnbuckle 43, the arm and the mold board attached thereto may be moved about its pivoting point to any desired angle, as shown in dotted lines. In this manner a wall having a tapered face of any desired degree of angularity may be constructed. It is necessary in this case, however, to move the pivotal point of the arm 39, inwardly toward that of the arm 40, as each superimposed section is added, in order that the thickness of the wall be decreased in proper proportion to the degree of taper employed.

25. As a further feature of my invention, I provide a set of specially designed mold boards 45 (Fig. 8), adapted for use in constructing concrete fence posts. These boards have their upper and lower margins inclined at an angle to afford the proper degree of taper to the posts to be constructed. The boards are provided with angle members 46, by means of which the boards may be secured to the frame members of the mold, in the same manner as the boards hereinbefore described. As a preferably construction, I also provide gates 47 and 48, at the ends of the boards, for the purpose of providing a proper end support for the post. The construction and manner of mounting the gates being the same as before set forth, a detailed description is thought to be unnecessary. To construct a fence post the mold would be placed upon a flat surface with the gates properly inserted in the ends of the mold boards, the space would be filled with concrete and the upper surface of the concrete properly leveled to coincide with the upper margins of the boards. When the concrete has become sufficiently hard the mold is released in the usual manner from the completed post.

30. It is to be understood that the details of construction of a concrete mold embodying my invention may be variously modified without departing from the spirit of the invention and for that reason I do not wish to be limited to the construction herein described and illustrated, except in so far as specifically pointed out in the appended claims.

I claim as my invention:

1. A concrete mold, comprising mold-boards spaced apart to receive concrete be-

- ween them, a supporting frame transverse to said boards, two arms on said frame which extend below the same and are attached to the mold-boards, one of said arms having pivotal connection with the frame, and an operating lever pivoted to the frame and adapted to have bearing engagement with said pivoted arm, and to be moved to swing said arm in one direction, and to lock the same from movement, said arm being provided with means for operatively connecting the same to said lever when moved to swing said arm in the opposite direction. 5
2. A concrete mold, comprising mold-boards spaced apart to receive concrete between them, a supporting frame transverse to said boards, two arms on said frame extending below the same and attached to the mold-boards, one of said arms having pivotal connection with the frame, and an operating lever pivoted to the frame and adapted to have bearing engagement with a surface of the pivoted arm, said lever acting to swing the arm in one direction and to lock the same from movement, said arm being provided with a link adapted to engage said lever when released from bearing engagement with said arm, to swing said arm in the opposite direction. 10
3. A concrete mold, comprising mold-boards spaced apart to receive concrete between them, a transverse supporting frame, two arms on said frame extending below the same and attached to the mold-boards, one of said arms having pivotal connection with the frame, and an operating lever pivoted to the frame and having its shorter portion in position to have bearing engagement with the pivoted arm; said operating lever being pivoted to swing on an axis parallel with the pivot of the pivoted arm, and said shorter arm of the operating lever being adapted to be brought into position at right angles to the pivoted arm, for locking the board to which it is attached, in operative position, said pivoted arm being provided with a link adapted to engage said lever, to swing said arm from its operative position. 15
4. A concrete mold, comprising mold-boards spaced apart to receive concrete between them, a transverse supporting frame consisting of upper and lower rigidly connected frame members, two arms connected with said frame, one of said arms being pivoted to the lower member of the frame, and an operating lever pivoted to the upper member of the frame, and acting on the upper end of the pivoted arm to swing the same into and out of operative position; said pivoted arm being provided below the upper frame member with a transversely extending link member, and the operating lever being adapted to act in one direction on the same pivoted arm and in the opposite direction of said link member for swing- 20
- ing the lower end of said pivoted arm inwardly and outwardly. 5
5. A concrete mold, comprising mold-boards spaced apart to receive concrete between them, a transverse supporting frame having upper and lower, rigidly connected, frame members, two arms connected with said frame, one of said arms being pivoted to the lower member of the frame, and an operating lever pivoted to the upper member of the frame, and acting on the pivoted arm to swing the same into and out of operative position; said pivoted arm being provided adjacent to the upper frame member with separated bearing surfaces facing toward each other, and the shorter arm of said operating lever being adapted to act on said bearing surfaces for shifting the pivoted arm into and out of operative position and to be brought into locking relation with one of said bearing surfaces, for holding the lower end of the pivoted arm rigidly from outward movement. 25
6. A concrete mold, comprising mold-boards spaced apart to receive concrete between them, a transverse supporting frame comprising upper and lower, rigidly connected, frame members, each consisting of two parallel parts or bars, two arms extending between the parallel parts of the frame members, one of said arms being pivoted between the parts of the lower frame member and extending at its upper end between the parts of the upper frame member, and an operating lever pivoted between the parts of the upper frame member, and having a shorter arm adapted to act upon the upper end of the pivoted frame member and to come into transverse, locking relation thereto when the lower end of said pivoted arm is in its inward position. 30
7. A concrete mold, comprising two mold-boards spaced apart to receive concrete between them, a transverse supporting frame comprising upper and lower, rigidly connected, frame members, two arms which are pivoted to and extend below the frame and are attached to the mold-boards, a turn-buckle adjustably connecting the frame with one of said arms, and means acting on the other arm to swing the mold-board thereon into and out of operative position and lock said board in operative position. 35
8. A concrete mold, comprising mold-boards spaced apart to receive concrete between them, a transverse supporting frame comprising upper and lower, rigidly connected, frame members, arms pivoted to the lower frame member and attached at their lower ends to the mold boards, a turn-buckle adjustably connecting the upper part of one of said arms with the frame, an operating lever pivoted to the upper member of the frame and acting on the upper end of the other of said arms, to swing the mold board. 40

attached thereto into and out of operative position and lock the said mold board rigidly from outward movement when in operative position.

5. 9. A concrete mold, comprising mold-boards spaced apart to receive concrete between them, a transverse frame member, and arms on the frame-member supporting said boards, at least one of said mold boards 10 being provided with a rabbet at its lower margin, adjacent to one of its ends, to form an end-portion of reduced width.

15. 10. A concrete mold, comprising mold-boards spaced apart to receive concrete between them, a transverse frame member, arms on the frame-member supporting said mold-boards, a transverse gate-member, and means for removably supporting said gate-member between said mold-boards, at least 20 one of said mold-boards being provided at its lower margin with a rabbet located adjacent to said gate-member, and forming an end-portion on the board of reduced width.

11. A concrete mold, comprising mold-boards spaced apart to receive concrete between them, a frame member to which said

mold-boards are attached, and a gate member adapted to be removably mounted at the ends of said mold-boards, at least one of said mold-boards being provided at its 30 lower margin with a rabbet extending inwardly from the end thereof adjacent to the said gate-member, a distance substantially equal to the distance between the adjacent faces of the said mold-boards. 35

12. A concrete mold, comprising mold-boards spaced apart to receive concrete between them, a transverse frame member, and arms on said frame member supporting said mold-boards, at least one of said mold-boards being reduced in width at one of its 40 ends and having in the lower edge of its narrow end portion a notch to receive a reinforcing wire.

In testimony, that I claim the foregoing 45 as my invention I affix my signature in the presence of two witnesses, this 19 day of Dec. A. D. 1913.

WILLIAM H. TUOHY.
